US0D1056435S

(12) **United States Design Patent** (10) **Patent No.:** **US D1,056,435 S**
(45) **Date of Patent:** ** *Jan. 7, 2025

(54) **GOLF SHOE OUTSOLE**

(71) Applicant: **Acushnet Company**, Fairhaven, MA (US)

(72) Inventors: **Jean-Marie Bidal**, Bridgewater, MA (US); **John F. Swigart**, Portland, OR (US)

(73) Assignee: **Acushnet Company**, Fairhaven, MA (US)

(*) Notice: This patent is subject to a terminal disclaimer.

(**) Term: **15 Years**

(21) Appl. No.: **29/819,362**

(22) Filed: **Dec. 14, 2021**

Related U.S. Application Data

(63) Continuation of application No. 29/717,117, filed on Dec. 15, 2019, now abandoned, which is a continuation of application No. 29/694,182, filed on Jun. 7, 2019, now Pat. No. Des. 933,347.

(57) **CLAIM**

The ornamental design for a golf shoe outsole, as shown and described.

DESCRIPTION

FIG. 1 is a bottom perspective view of the golf shoe outsole of this invention;

FIG. 2 is a lateral side view of the golf shoe outsole of this invention;

FIG. 3 is a medial side view of the golf shoe outsole of this invention;

FIG. 4 is a front view of the golf shoe outsole of this invention;

FIG. 5 is a rear view of the golf shoe outsole of this invention;

FIG. 6 is a bottom view of the golf shoe outsole of this invention; and,

FIG. 7 is a top view of the golf shoe outsole of this invention. In FIGS. 1-7, the broken lines show environment on the top surface of the shoe, including the laces and logo, and form no part of the claimed design.

1 Claim, 6 Drawing Sheets
